Design No. 18,195, dated March 20, 1888.

UNITED STATES PATENT OFFICE.

JOHN SLATER, OF BURSLEM, COUNTY OF STAFFORD, ENGLAND.

DESIGN FOR A WATER-CLOSET.

SPECIFICATION forming part of Design No. 18,195, dated March 20, 1888.

Application filed February 10, 1888. Serial No. 263,646. Term of patent 3½ years.

To all whom it may concern:

Be it known that I, JOHN SLATER, a subject of the Queen of Great Britain, residing at Burslem, county of Stafford, England, have invented a certain new and original Design for Water-Closets, fully described and represented in the following specification and the accompanying illustrations, forming a part of the same.

10 The present invention relates to a design for the configuration and ornamentation of the bowl or body of a water-closet.

The essential or characteristic features of the design can be best understood by reference 15 to the accompanying illustrations, in which—

Figure 1 is a front and Fig. 2 a side elevation of a closet embodying the design.

Referring to said figures it will be seen that the closet consists, essentially, of three parts—20 a pedestal portion, A, a supporting-column, B, which rises from the pedestal, and a body or bowl portion, C, which surmounts and is supported by the column B. The bowl or body portion C is of slightly oval form, with walls 25 that flare outward at the sides and rear end, so as to project beyond the support B, as shown in Figs. 1 and 2, while its front end, d, inclines inward and rearward, as shown in Fig. 2. The

supporting-column B, which is of sufficient breadth from front to rear to support the bowl 30 for the greater portion of its length, gradually increases in thickness at its front from the pedestal to its point of union with the bowl C, so as to present in front elevation a substantially-uniform flare from the pedestal to 35 the top of the bowl, as shown in Fig. 1. The configuration of the supporting column and bowl is provided at its front with ornamentation consisting of the figure, a, of an urn or a vase, formed either in relief or embossed; and 40 in addition to this the sides and front are provided with any suitable ornamentation, either in relief or embossed, as shown at b and c.

What I claim is—

A design for the configuration and ornamentation of a water-closet, consisting of the supporting-column B and bowl C, having the figure of an urn or vase formed on its front, substantially as shown and described.

In testimony whereof I have hereunto set my 50 hand in the presence of two subscribing witnesses.

JNO. SLATER.
